UNITED STATES PATENT OFFICE.

HARRY J. CRINER, OF BLOOMINGTON, ILLINOIS.

REMOVABLE WRINGER MECHANISM.

Application filed July 20, 1921. Serial No. 486,157.

To all whom it may concern:

Be it known that I, HARRY J. CRINER, a citizen of the United States of America, residing at Bloomington, in the county of McLean and State of Illinois, have invented certain new and useful Improvements in Removable Wringer Mechanism, of which the following is a specification.

My invention relates to removable wringer mechanism, or more particularly to gear mechanism and connections therefor.

The object of my invention is in the provision of special mechanism in connection with the power connections of a washing machine and wringer mechanism whereby any chances of accident, due to the sudden revolving of the wringer mechanism when it is shifted to various angles about its axis, is obviated.

Another object of my invention is in the provision of special mechanism that automatically throws out of engagement the power connection between the power plant of a washing machine and the wringer mechanism when said mechanism is being shifted to various operative positions about its axis, and when set in said operative position to automatically release said neutral positioning of the power shaft and wringer mechanism.

Other objects of my invention will appear in the following description in connection with the annexed drawings, in which,

Fig. 1 is a front elevation of the device with several portions shown in section for a more detailed view thereof;

Fig. 2 is a sectional view taken on the line A—A of Fig. 1.

Referring to the drawings, it will be seen that I have shown neither the washing machine and its power connections nor the wringer mechanism, the above merely being conventional in their relation with my device, and no form thereof being essential.

A bracket is shown at B, said bracket including a supporting member 10 for the power shaft and the wringer mechanism (not shown), also a gear housing 11 and a cylindrically shaped base portion 12 capable of being seated in a similarly shaped aperture in the washing machine. The base member 12 forms a supporting means for the gear connections and wringer mechanism and also a housing for the power connection between the power shaft of the washing ma-

chine and the power connections for the wringer mechanism.

An abutment or seat is shown at 13 determining the proper positioning of the removable wringer mechanism with relation to the washing machine. The power shaft of the washing machine (not shown) has engagement with a tooth clutch 14 held in tensioned engagement therewith by a coil spring 15, said spring tending to hold the vertically positioned shaft 16 downwardly. The shaft 16 has bearing surface in the portion 17 of the bracket member.

A collar 18 surrounds the shaft 16 just above the bearing portion 17, said collar lying within the portion 19 of the bracket B, said portion 19 having pivoted therein as at 20 the lever 21 which has its forked inner end 22 in engagement with a notched portion 23 of the collar 18. Inasmuch as a key 24 is fixed in the shaft 16 just above the collar a downward movement of the lever 21 to the dotted line position shown in Fig. 1 will throw the collar 18 against the key 24 and hence raise the tensioned vertical shaft 16 a certain amount.

The collar 18 within which the shaft 16 rotates has an outwardly projecting arm 25 which lies between the forked ends 22 of the lever 21. Projecting downwardly and outwardly and integral with the arm 25 is a lug 26, said lug normally seating in one of the portions 27 and adapted to be raised, upon the upward movement of the collar 18, from its seat and shifted as desired.

A gear wheel 28 is mounted on the upper end of the shaft 16 and is always held in operative connection therewith due to the key and slot connection 29 and 30 respectively. It may be seen that the vertically positioned shaft 16 has merely a sliding connection with this gear wheel and when moved upwardly by the lever 21 will have the projection 31 at its upper end thrown into engagement with the clutch 32 which has connection with the power shaft 33 for the wringer mechanism (not shown). Gear wheels 34 and 35 are loosely mounted on the horizontally positioned power shaft 32 and in connection with the cam member 36 operated by the lever 37 form the means for operating the power shaft 33 in either direction desired.

The operation of the device is as follows: When the wringer mechanism including

the device here shown is placed upon the washing machine, connection is made between the power shaft (not shown) of the washing machine and the vertically positioned shaft 16 which constantly drives the gear wheel 28, and when it is desired that the wringer mechanism be operated this is accomplished by merely moving the lever 37 which throws the clutch 32 into connection with one of the gear wheels 34 and 35, the gear engaged determining the direction of movement of the wringer rolls. The above is merely a conventional mounting for a removable wringer mechanism. It is desired, however, when in the operation of washing to move the wringer mechanism at various angles about its axis and it is also necessary that in this moving of the wringer from one angle to another that there be no danger of the wringer whirling about due to the constantly revolving of the power shaft and also the shaft 16.

With the device above described whenever it is desired that the wringer be moved, the lever 21 is thrown downwardly, thus thrusting the upper end 31 on the shaft 16 into engagement with the clutch 32 on the power shaft 33. However, should the clutch at that time be in engagement with one of the gear wheels 34 or 35 it would be impossible to force the projection 31 upwardly as it would engage one of the projecting portions 38 and 39 of the clutch. Thus it may be seen that before moving the wringer from one position to another it is absolutely necessary that the clutch 32 be thrown into a neutral position and when in this neutral position there is no power transmitted to the wringer mechanism and thus any possibility of its revolving in any direction is made impossible.

When the projection 31 is thrown into engagement with the clutch 32 and is holding it in such neutral position the lug 26 of the collar 18 has been raised from its seat in the bracket on the washing machine and the whole wringer mechanism is capable of being moved to any angle that is desired, or, rather, to any other seat and when moved to such position the lug 26 will be positioned, or, rather, will fall into another seat portion due to the downward tensioning of the shaft 16 by the coil spring 15 and also when in this seated position the projection 31 will be automatically withdrawn from the clutch 32 and the lever 21 will be thrown upwardly to its normal position. Thus we will see from the safety mechanism which has been described that any movement of the wringer mechanism about its axis without throwing into engagement this special safety mechanism is prevented and when this safety mechanism is thrown into action any possible and dangerous revolving of the wringer mechanism is prevented.

What I claim is:

1. In a safety wringer mechanism, in combination, a bracket member including a horizontally disposed shaft having loosely mounted thereon two gears, a clutch mounted between said gears, means for throwing said clutch into engagement with either gear, a vertically positioned and tensioned shaft disposed below said first named shaft and having its upper end shaped in such manner that it is capable of engagement with the clutch mounted thereabove, a gear slidably mounted on the upper end of said vertically positioned shaft and having engagement with the first named gears, a collar surrounding said vertical shaft, said collar having an outwardly and downwardly projecting lug member, a key member in the vertical shaft just above said collar, and a lever pivoted to said bracket member and having such connection with the collar that movement of said lever is capable of raising or lowering the vertically positioned shaft.

2. In a device of the class described, in combination, a bracket member including therein a horizontally positioned shaft, gear wheels loosely mounted thereon, a clutch member disposed between said gears, means for throwing said clutch in engagement with either gear, a vertically positioned shaft disposed below said horizontal shaft, said vertical shaft having its upper end capable of engagement with the clutch member, a gear loosely mounted on the upper end of said shaft and having engagement with said first named gears, and mechanism including a collar having an outwardly projecting engagement member and a pivotal lever whereby movement of the bracket member about its axis is prohibited until the vertical shaft is raised to such an extent that its upper end will engage the clutch on the horizontally positioned shaft.

3. In a device of the class described, a removable swinging wringer, a tubular casing adapted to receive the wringer in operative relation therewith, a power shaft in the tubular casing, a wringer shaft in the removable wringer, a clutch on the wringer shaft, said clutch being provided with an annular groove, a reciprocating shaft providing the connecting means between the power shaft and the wringer shaft, a projection on the reciprocating shaft adapted to enter said groove to lock said clutch, a lever member pivotally mounted on the wringer and having selective engagement with the tubular casing and a connecting means between the lever and the reciprocating shaft, whereby the shaft is operated to lock the clutch.

4. In a device of the class described, in combination, a tubular casing having a power shaft therein, a wringer adapted to engage said tubular casing and having

power connections adapted to engage the power shaft and including clutching mechanism co-operating with the power connections to effect movement of the wringer in either direction, and manually operated means for releasing the power connections during the swinging movement of the

wringer and at the same time holding the clutch connections of the wringer in a neutral position.

10

In testimony whereof I have affixed my signature.

HARRY J. CRINER.
